[57] CLAIM

The ornamental design for a food package, as shown and described.

DESCRIPTION

FIG. 1 is a perspective view of a food package illustrating our new design;

FIG. 2 is a side elevational view of a food package, the opposite view is a mirror image thereof;

FIG. 3 is a top plan view thereof;

FIG. 4 is a side elevational view thereof;

FIG. 5 is a front elevational view thereof;

FIG. 6 is a rear elevational view thereof;

FIG. 7 is a bottom plan view thereof; and,

FIG. 8 is a cross sectional view taken along lines 8—8 of FIG. 7.

The broken line showing of a container is for illustrative purpose only and forms no part of the claim.

FIG. 1
